EGG CARTON

Bent Moller, Vaerlose, Denmark, assignor to
Aktieselskabet Brodrene Hartmann

Filed Mar. 16, 1973, Ser. No. 341,937

Claims priority, application Denmark Feb. 28, 1973

Term of patent 14 years

Int. Cl. D9—03

U.S. Cl. D9—190

FIG. 1.

FIG. 3.

FIG. 4.

FIG. 5.

FIG. 6.

FIG. 8.

FIG. 7.

FIG. 1 is a top view of an egg carton showing any new design in an open position;

FIG. 2 is a bottom plan view thereof;

FIG. 3 is a front perspective view in a closed position;

FIG. 4 is a top plan view thereof;

FIG. 5 is a front elevational view thereof;

FIG. 6 is a rear elevational view thereof;

FIG. 7 is an elevational view looking from the left of FIG. 5;

FIG. 8 is an elevational view looking from the right of FIG. 5;

FIG. 9 is a bottom plan view thereof;

FIG. 10 is a sectional view taken on the line 10-10 of FIG. 4;

FIG. 11 is a sectional view taken on the line 11-11 of FIG. 4;

FIG. 12 is a sectional view taken on the line 12-12 of FIG. 4; and

FIG. 13 is a sectional view taken on the line 13-13 of FIG. 4.

I claim:

The ornamental design for an egg carton, substantially as shown.
